(Cl. D86—10)

To all whom it may concern:

Be it known that I, Paul E. Flato, a citizen of the United States of America, residing in New York city, county of New York, and State of New York, have invented a new, original, and ornamental Design for a Compact or Similar Article, of which the following is a specification, reference being had to the accompanying drawing, forming part thereof, wherein

I claim:

The ornamental design for a compact or similar article, substantially as shown.

PAUL E. FLATO.
